UNITED STATES PATENT OFFICE.

JOHN CHANTRELL, OF BRIDGEPORT, CONNECTICUT, ASSIGNOR TO HAZEL-TINE & CHANTRELL, OF SAME PLACE.

RATCHET BRACE.

SPECIFICATION forming part of Letters Patent No. 286,683, dated October 16, 1883.

Application filed July 3, 1883. (Model.)

To all whom it may concern:

Be it known that I, JOHN CHANTRELL, of Bridgeport, in the county of Fairfield and State of Connecticut, have invented certain new and useful Improvements in Ratchet Braces; and I do hereby declare the following to be a full, clear, and exact description of the invention, such as will enable others skilled in the art to which it appertains to make and use the same.

My invention relates to an improvement in ratchet braces, the object of the same being to provide a device that will combine simplicity and economy in construction with durability and efficiency in use; and with these ends in view my invention consists in the parts and combination of parts, as will be more fully described, and pointed out in the claims.

In the accompanying drawings, Figure 1 is a view in side elevation of my improved ratchet brace. Fig. 2 is a plan view on the line *x-x* of Fig. 1. Fig. 3 is a similar view, showing the shifting-cap removed. Fig. 4 is a view of the stock with the chuck, ratchet, and pawls removed. Fig. 5 is a perspective view of the chuck. Fig. 6 is a view of the ratchet-wheel, and Fig. 7 is a detached view of the pawls.

A represents the brace-stock, the end B of which is enlarged and provided with the circular bearing C, in which the upper end of the chuck D is secured. This bearing is elongated to afford a firm support for the end of the chuck, and the latter is adapted to rest snugly therein for the purpose of preventing any lateral or wobbling motion. The inner end of the face B of the stock, or that portion thereof above the bearing C when the stock is held in a vertical position, is recessed for the reception of the ratchet-wheel and the pawls F, the former being rigidly keyed to the upper end of the chuck, while the latter are fulcrumed to the stud H of the bit-stock. The upper end, *a*, of the chuck D is reduced in size to form a seat for the ratchet-wheel E, and is provided with the rigid keys *b*, adapted to enter corresponding grooves, *c*, in the ratchet-wheel E for the purpose of preventing the wheel from moving independently of the chuck. The recess G of the stock A is sufficiently deep

for the ratchet-wheels and pawls to rest there-in flush with the upper surface of the end B, and is preferably shaped to conform to the contour of the wheel and pawls.

H is a stud situated in the recess and set 55 into or formed integral with the stock. This stud is sufficiently large to withstand the strain necessarily exerted thereon, and is provided with a female-screw-threaded opening for the reception of the screw I, which secures the 60 shifting-cap J in place. The pawls F are shaped alike, and both are provided on their adjacent or inner ends with the semicircular recesses, in which the stud H rests. These 65 pawls are arranged on opposite sides of the stud, so as to engage, respectively, the opposite sides of the ratchet-wheel for the purpose of turning the chuck in opposite directions, and also for locking the chuck against movement independently of the stock. The stud 70 H forms the axis for both pawls, and the latter are partly encircled by a single flat spring, K, which actuates both pawls. The pawls, when placed in position on the stud H, form a semicircle, and the spring K is curved in a 75 similar manner and situated in rear of and bears against the convex faces thereof, and tends constantly to force the pawls against the ratchet-wheels.

The pawls F are provided on their convex 80 faces, preferably about midway their lengths, with the bent fingers L. These fingers pass outwardly through the notches *d* in the end B of the stock, and then bent upwardly for the purpose of engaging the shifting-cap. The 85 chuck D is passed upwardly through the bearing in the end B of the stock, and the ratchet-wheel is then secured thereon. These parts are secured together and to the stock of the brace by the headed screw M, which latter is 90 screwed into the female-screw-threaded opening *e* of the chuck D, and bears on the ratchet-wheel, and prevents the chuck from moving longitudinally. The shifting-cap J is then 95 placed in position over the wheel and pawls, and protects the parts from dust and dirt, and also serves as a means for shifting and locking the pawls in any desired adjustment. This cap, at its outer end and sides, conforms in shape to the contour of the end and sides 100

of the stock, and is provided with a large circular opening, sufficiently large for the passage of the head of the screw M, and a smaller oblong opening, f, for the passage of the shank 5 of the screw I, which latter, as before stated, secures the shipping-cap in place.

The rear end of the cap J is provided centrally with the inwardly-projecting thumb-piece g, by means of which the cap is shifted, 10 and near its opposite sides with the slots h, in which the upper ends of the fingers L of the pawls F rest. When the parts are secured in position, the cap-piece J rests well down around the head of the screw M, and the latter forms 15 the axis of the said cap-piece, while the small screw holds it in position and limits its movement. When the thumb-piece g rests in the longitudinal center of the stock, the spring K holds both pawls in contact with the ratchet- 20 wheel, and consequently locks the latter to the chuck. When, however, the shipping-cap is turned on its axis to one side or the other, one of the pawls is disengaged from the wheel, which leaves the stock free to be turned in one 25 direction independently of the chuck. When the thumb-piece g of the shifting-cap J rests in the longitudinal center of the stock, both of the fingers L of the pawls F rest against the outer confines of the slots h in the cap J and 30 the slots d of the stock, and both pawls are in engagement with the ratchet, and consequently prevent the chuck from moving independently of the stock, thereby forming an ordinary bit-stock. When it is desired to convert the brace 35 into a ratchet brace, the cap is turned in the desired direction, and one of the fingers L of the pawls F is moved from the outer side of the slot h to the inner side thereof. This movement of the finger L draws its pawl away 40 from the wheel, where it is held until the shifting-cap is again turned. This shifting-cap can be provided with a small depending lug adapted to register with a series of grooves in the stock A, for the purpose of holding it in 45 position against accidental movement after the parts are adjusted.

Any style of chuck can be employed in connection with the stock or chuck, or the ratchet arrangement can be applied to wrenches and 50 screw-drivers without materially altering its structure or arrangement. Ordinarily the ratchet arrangement of chucks is set into an open slot formed in the end of the stock and rigidly secured therein by rivets. This method, besides being expensive and weakening the structure, also renders it impossible to get 55 at the parts for the purpose of removal and repair without first removing the rivets; but by my arrangement I am enabled to separate 60 all the parts by the removal of the two screws, thereby enabling an unskilled person to take the device apart and put it together in a few moments without the use of any tools other than a screw-driver.

65 This device is exceedingly simple, is durable and effective in use, and can be manufactured at a small initial cost.

I am aware that a ratchet brace has been constructed as follows: The chuck has an enlarged head at its upper end, in which are 70 formed two recesses. In each recess is pivoted an independent pawl, the free end of which is thrown outwardly by a spiral spring, one end of which engages with the pawl, while the other end is seated in a recess formed in the head of the chuck. The outer end of the pawl engage internal teeth or projections formed on the head of the stock. The position of the pawls is regulated by a cap, which is constructed with cam-slots to receive pins 80 on the pawls; hence I would have it understood that I make no claim to the construction and arrangement of parts above described. In my improved construction the chuck is provided at its upper end with a flanged collar, 85 to which is removably secured a ratcheted wheel. The latter, being independent and removable, is susceptible of being produced in a more economical and in a more highly-finished manner than if formed on the interior of 90 the end or head of the stock. Again, in my improvement the pawls are provided with curved faces, forming half-bearings, which engage the opposite sides of a single circular stud, which insures a stronger and cheaper 95 construction than to bore through and separately pivot each pawl to the chuck-head. Further, in my improvement a single elliptic spring serves for both pawls, while in the construction described separate and independent 100 springs are required for each pawl, and, by reason of the limited space allowed for their expansion and contraction, are liable to become set or broken in use.

Having fully described my invention, what 105 I claim as new, and desire to secure by Letters Patent, is—

1. The combination, with a bit or other stock having an elongated bearing and a recessed face above the bearing, of a chuck, a ratchet-wheel secured to the chuck, pawls situated within the recess and adapted to engage the ratchet, a spring for holding the pawls in contact with the wheel, and a cap for shifting the pawls and forming a cover therefor.

2. The combination, with a bit or equivalent stock having an elongated bearing and recessed face, and a stud situated alongside of the bearing within the recess, of a chuck, a ratchet-wheel secured to the chuck, pawls the inner 110 ends of which embrace the stud, while the outer ends are adapted to bear on the ratchet, and a shifting-plate for shifting the pawls, substantially as set forth.

3. The combination, with a bit or equivalent stock, constructed as described and provided with a stud, of a chuck, the upper end of which is provided with a feather or feathers, a ratchet-wheel secured on the feathered end of the chuck, pawls the inner ends of 120 which embrace the stud, while their outer ends are adapted to engage the ratchet, a spring for holding the pawls in contact with the ratchet, and a shifting-plate for shifting the pawls.

4. The combination, with the stock, constructed as described and provided with a stud, of the chuck provided with a feather or feathers, a ratchet-wheel secured to the feathered end of the chuck, pawls the inner ends of which embrace the stud, bent fingers secured to the pawls, a spring for holding the pawls in contact with the ratchet, and a shifting-cap adapted to engage the bent arms of the pawls for the purpose of shifting or adjusting them, substantially as set forth.

5. The combination, with the stock provided with a stud, of the chuck, ratchet-wheel, headed screw for securing the ratchet-wheel to the chuck, and forming an axis for the shifting-plate, pawls provided with arms, the spring for holding the pawls in contact with the ratchet-wheel, and the shifting-cap, substantially as set forth.

20 6. The combination, with the stock and stud secured thereto, of the chuck, ratchet-wheel, headed screw for securing the ratchet to the

25 chuck, and forming an axis or pivot for the shifting-cap, pawls provided with bent arms, a spring for holding the free ends of the pawls in contact with the ratchet-wheel, the shifting-cap, and screw for holding it in position, substantially as set forth.

7. The combination, with a tool-handle provided with a recessed bearing, a ratchet-wheel situated within said bearing, two pawls having the same pivotal bearing, a single spring acting on both pawls, a plate for throwing either or both pawls out of engagement with the ratchet, of a bit or tool stock connected with the ratchet by feather-and-spline engagement, substantially as set forth.

In testimony whereof I have signed this specification in the presence of two subscribing witnesses.

JOHN CHANTRELL.
